[57] **CLAIM**

The ornamental design for a pipe clamp, as shown and described.

DESCRIPTION

FIG. 1 is a perspective view of a pipe clamp showing our new design;
 FIG. 2 is a front elevational view;
 FIG. 3 is a right side elevational view;
 FIG. 4 is a rear elevational view;
 FIG. 5 is a top plan view;
 FIG. 6 is a bottom plan view;
 FIG. 7 is a left side elevational view; and,
 FIG. 8 is a right side elevational view of a second embodiment of our new design, the only difference being the parallel disposition of the screw.
